(Model.)

H. C. RICE.
Pencil Sharpener.

No. 230,338.

Patented July 20, 1880.

UNITED STATES PATENT OFFICE.

HENRY C. RICE, OF EASTHAMPTON, MASS., ASSIGNOR OF ONE-HALF OF HIS
RIGHT TO M. H. JAMIESON, OF MIDDLETON, CONN.

PENCIL-SHARPENER.

SPECIFICATION forming part of Letters Patent No. 230,338, dated July 20, 1880.

Application filed May 24, 1880. (Model.)

To all whom it may concern:

Be it known that I, HENRY C. RICE, of Easthampton, in the county of Hampshire and State of Massachusetts, have invented certain new and useful Improvements in Pencil-Sharpener; and I do hereby declare the following to be a full, clear, and exact description of the invention, such as will enable others skilled in the art to which it pertains to make and use it, reference being had to the accompanying drawings, which form part of this specification.

My invention relates to an improvement in pencil-sharpener; and it consists in the combination of a shaft having a sharpener attached to its inner end so as to revolve with it, a rotary file which is carried around by the shaft, and which is caused to revolve independently of the shaft by means of a suitable gear or device of its own, and a sliding carriage which clamps the pencil and moves it forward toward the sharpener, as will be more fully described hereinafter.

The object of my invention is to provide a means for cutting away the wood on the pencil, and a separate and independent device for sharpening the lead at the same time, so that the point will be perfectly finished at the same time that the wood is cut away without any danger of being broken or having to be separately finished afterward, as is the case with many of the sharpeners now in use.

Figure 1 is a side elevation of my invention, partly in section. Fig. 2 is a plan view of the same. Fig. 3 is an end view of the carriage for holding the pencil.

A represents a suitable base, upon which the standard B is mounted. In the upper part of the standard is formed a bearing, C, for the shaft D, which has the driving-wheel E upon one end and the conical sharpener F upon the other. This sharpener does not differ materially from many of those now in use, with the exception that the blade which cuts away the wood is longer, and is provided with a set-screw for feeding it forward and another set-screw for clamping it tightly against the projecting part of the frame upon which it is held. Projecting from one side of this shaft, 50 inside of the circular flange H, which is formed

on the top of the standard B, is an arm, I, which extends outward any suitable distance toward the inner edge of this recess, and upon which arm is pivoted an adjustable plate, K, in which plate is journaled a short shaft, on 55 which are placed a friction-wheel, of rubber or other suitable material, for bearing against the inside of the flange H, and a rotary file, L, which has its outer edge tapered, as shown. By having this plate K made adjustable a finer 60 adjustment of the file can be given. This wheel of rubber, by bearing against the inside of the recess in the top of the standard, causes the file to revolve in the opposite direction from the shaft, and independently of the shaft, 65 upon its own axis. This revolving file has its smaller edge to come just flush with the opening through which the point of the pencil projects in the inner end of the sharpener, and then the remainder of its edge forms the exact 70 taper which is to be given to the point. As the point of the pencil is forced inward the knife cuts away the wood at the same time that the revolving file gives a most perfect taper to the end of the lead.

In order that the pencil may always be held not only perfectly straight, but be fed forward in a steady manner, there is a stand, N, made, upon the top of which are formed the two guides O. Moving back and forth upon these 80 two guides upon this stand, and just opposite to the fastener, is a carriage, Q, for holding the pencil while it is being sharpened. This carriage is pivoted upon one of the guides, so that it can be turned freely over upon one 85 side, and consists of the bottom piece, which is attached to the guide, two jaws, R, and a latch, S. In between these two pivoted jaws is a block or rubber, T, which has a suitable recess formed in its upper part for receiving 90 the pencil. When the two jaws are pressed together, so that the latch can fasten them in that position, the rubber clamps the pencil, so as to hold it very firmly and securely in position, and yet without injuring the finish of the 95 pencil, and so as to allow the pencil to yield slightly in any direction, so as to accommodate itself to the cutter should it not be placed exactly in line with it. By means of this rubber clamp not only is the pencil not injured 100

in appearance, but the pencil is left free to move just sufficiently to have the point put upon it in the most perfect manner. Removably attached to the standard is the box V, which is placed just under the cutter, so as to catch all of the wood and the dust from the lead, and thus prevent a dirt and litter from being made.

Having thus described my invention, I claim—

1. In a pencil-sharpener, the combination of a shaft having a pencil-sharpener secured to its end and a file that is carried around by the shaft so as to sharpen the point of the pencil, substantially as shown.

2. In a pencil-sharpener, the combination of a shaft having a pencil-sharpener secured to its end with a revolving file that is carried around the point of the pencil, and provided with a means, substantially as described, for causing it to revolve in an opposite direction to the shaft, substantially as described.

3. In a pencil-sharpener, the combination of a shaft having a pencil-sharpener secured to its end, the arm I, a wheel to bear against the inside of the flange H, and a revolving file, L, the parts being arranged to operate substantially as set forth.

4. In a pencil-sharpener, the combination of a revolving shaft having a pencil-sharpener secured thereto, and a horizontally-moving carriage composed of the two hinged jaws R, recessed block of rubber T, and a holding-latch, S, substantially as specified.

5. The combination, in a pencil-sharpener, of a revolving sharpener, an oppositely-revolving file, a carriage for holding and feeding forward the pencil, and a box to catch the chips, substantially as shown and described.

6. The combination, in a pencil-sharpener, of a revolving shaft and a suitable bearing therefor, a pencil-sharpener, F, that is secured to one end of the shaft, and provided with a cutting-blade for paring away the wood of the pencil only, and a fly-wheel or crank that is secured to the other end of the shaft, substantially as set forth.

In testimony that I claim the foregoing I have hereunto set my hand this 11th day of May, 1880.

HENRY C. RICE.
